(57) **CLAIM**

I claim the ornamental design for a tapered arch plant stand, as shown and described.

DESCRIPTION

FIG. 1 is a perspective view of a tapered arch plant stand; FIG. 2 is a front view thereof; FIG. 3 is a back view thereof; FIG. 4 is a right side view thereof; FIG. 5 is a left side view thereof; FIG. 6 is a top view thereof; and, FIG. 7 is a bottom view thereof.

The broken lines in the drawings depict environmental subject matter that forms no part of the claimed design.
